UNITED STATES PATENT OFFICE.

HENRY F. HAYDEN, OF WASHINGTON, DISTRICT OF COLUMBIA.

IMPROVEMENT IN HOT-WATER HEATING APPARATUS.

Specification forming part of Letters Patent No. 147,771, dated February 24, 1874; application filed February 4, 1874.

To all whom it may concern:

Be it known that I, HENRY F. HAYDEN, of the city and county of Washington, District of Columbia, have invented certain new and useful Improvements in Hot-Water Heating Apparatus, of which the following is a full, clear, and exact description, reference being had to the accompanying drawing making part of this specification, in which—

Figure 1 represents a side elevation, partly in section, of the improved heater, showing the fire-pot, which is also an annular water-reservoir, in section. Fig. 2 is a plan or top view of the four-way or T-piece, showing the connection of the supply-pipe and vertical reservoir with the heating-coil. Fig. 3 is a plan view of the heater-coil and water-reservoir, and Fig. 4 is a vertical section through the furnace, showing the arrangement of the smoke-pipe relative to the grate and annular fire-pot.

Similar letters of reference denote corresponding parts wherever used.

The invention has for its object the improvement of that class of heaters in which the heat intended for use is generated by hot water contained within and circulating through a suitable arrangement of pipes and reservoirs; and the first part of the invention relates to a novel construction of the fire-pot, and to the arrangement of the same relative to its inclosing shell or case, and to the heating-chamber, whereby the amount of fuel required for heating the water is greatly reduced, while at the same time the admission of the gases to the heating-chamber is effectually prevented, and consists in making the fire-pot in the form of an annular water-reservoir surrounding the fire, and surrounded by an inclosing-case in such manner as that the products of combustion are compelled to pass up, through, over, and down outside of said annular reservoir or fire-pot, and connecting both ends of the heating-coil outside of the heating-chamber with said annular water-reservoir, as hereinafter described. The second part of my invention relates to the construction and arrangement of the heating-coil and water and vapor reservoirs, and consists in making the heating-coil or pipe, which is connected with the annular fire-pot, and through which the main circulation of water takes place, of uniform or substantially uniform diameter, and combining

therewith reservoirs of sufficient capacity to prevent the ebullition of the water, and to receive the vapor arising therefrom, said reservoirs being connected with the coil by pipes of less diameter in such manner as not to interfere with or impede the circulation through the heating-coil. The third part of the invention consists in a novel arrangement of condensing or overflow reservoir and overflow-pipes constituting a safety apparatus, as hereinafter described; and the invention consists, lastly, in certain details of construction and arrangement hereinafter fully explained.

In the accompanying drawing, A represents an annular base-plate, forming within it the ash-pit, and provided with suitable openings for the admission of air and the removal of the ashes in any convenient or preferred manner. Upon this is placed the fire-pot B, which is made in the form of an annular or double-walled cylinder, either cast or made of boiler-iron, as preferred, the annular space B' being closed at the top and bottom, and forming a water-reservoir surrounding the central fire-chamber, which is open at top and bottom, except as it is closed at the bottom by a grate, C, of any usual or preferred construction. The fire-pot B is inclosed within a casing, D, which, by preference, is made of galvanized or cast iron, and coated with a non-conductor of heat; but it may be of any suitable material, and, being of greater diameter than the water-tank and fire-pot, leaves an annular space, D¹, around the same, to permit the products of combustion after passing up through and over the said reservoir to pass down again outside of the same, and to escape at or near the bottom of the casing, or upon or about upon a level with the grate, as shown in Fig. 4. An opening, d², is provided in the top of the casing D to permit the introduction of the fuel, said opening being surrounded by a rim or flange, d, which projects downward and inward for directing the fuel into the fire-pot, while at the same time said rim is sufficiently removed from the fire-pot to permit the products of combustion to escape around it, as shown by the arrow in Fig. 1. The furnace or fire-pot thus constructed is located outside of the heating room or chamber E, and has no connection therewith, except as it is afforded through the water-pipes G G¹, which are connected with the annular water-space

B', one at or near the top, and the other at or near the bottom of said space or reservoir, as shown. The heating-chamber E is tightly walled, or closed in by walls F, of brick, sheet metal, or other suitable or usual material, being perforated only to receive the necessary supply and exhaust water and air-pipes, and a tightly-fitting door affording access to the heating apparatus. The water-pipe or coil G has its lowest point at or near its connection with the annular reservoir B', and, rising thence, passes within the chamber E, where it is bent or made to assume a rectangular form, as at G², rising spirally until the desired height and the requisite amount of heating-surface are obtained, when it is turned outward and slightly downward, and is again connected with the annular water-space B' at or near the top of the same, as shown at G¹. Within the coil G is placed a vertical reservoir, H, connected at its lower end, by a small pipe, h, with the larger pipe G of the coil G², and at its upper end, by a similar pipe, h', with a horizontal second reservoir or chamber, I. The reservoir I is also connected with the coil G² at or near its highest point by a small pipe, i, and the reservoir I, at or near midway of its height, is provided with an overflow-pipe or pipes, i' i', which, extending downward within the coil, are connected at their lower ends with a condensing chamber or reservoir, K, to which, at or near its bottom, a drip or waste pipe, k, is connected, as shown. This condensing-chamber K may be made of a shape conforming to the shape of the coil, or to the walls or piers J on which said coil rests, but, by preference, is made rectangular in form, and in two parts, the lower part K forming the condensing-chamber proper, provided at its upper edge with a horizontal flange, l, and an upper part or cover, K', which is provided with a vertical rim or flange, l', forming an evaporating-pan for the reception of water, which is open and exposed to the action of the atmospheric air within the chamber E. The cover K' is secured to the bottom part by bolts or other fastenings, with any suitable packing interposed for making the condensing-chamber K tight. The pipe G may be provided at or near its lowest point, as at g², with a sediment trap or cock, through which the sediment may be drawn off when necessary. The supply-pipe g may be connected with the large or coil pipe G at or near its lowest point, either direct, as shown in Fig. 1, or through a T or cross-piece, G³, in the latter case the vertical reservoir H being also connected with said T, as shown in Fig. 2. Any suitable or preferred safety-valve arrangement may be applied, if desired; but ordinarily, with the capacity of the coil and reservoirs gaged to the size of the furnace, so as to prevent the ebullition of the water, no such safety arrangement will be required.

In filling the pipes and reservoir B', H, and I, the cocks g' k' to both the supply and waste-pipes will be opened, and the water, entering the pipe G, will flow into the annular reservoir

B' and vertical reservoir H, will gradually rise therein and in pipe G, forcing out the air therefrom, through the reservoir I and overflow-pipes i, until the water, rising in reservoir I to the level of said pipes i', overflows, and, passing down into the condensing-chamber K and out at the drip or waste pipe k, indicates that the apparatus is filled, when the supply-pipe is closed and the fire is kindled, the waste-cock k' being still left open to provide for the expansion of the water within the tank and pipe under the action of the heat until the desired temperature of the water—say, from 180° to 200°—is attained, when the waste-cock may be closed, and the apparatus is in operation, as follows, viz: The heat imparted to the water within the annular fire-pot B causing its expansion the hotter portions rise, and, passing out through the arm G' of the coil, enter the coil within the chamber, displacing the cold water at its highest point, while the cold water at the bottom of the coil, passing through arm G, enters the bottom of the annular water-space B', to be, in turn, heated and passed up and out at the top, thus creating a current or circulation through the coil, the heated water entering at the top and cooler portion passing out at the bottom of the coil, the heated water thus constantly crowding out and replacing the cold water, to be, in turn, gradually cooled and passed downward through the coil and back to the fire-pot. The reservoirs H and I are placed outside of the direct line or route of this circulation, but, being connected therewith by the smaller pipes, as explained, their contents are gradually mingled with and brought to the same temperature with the contents of the coil at the corresponding degree of elevation, and thus, while not interfering with or impeding the active circulation within the coil, they serve to prevent any rapid generation of steam while increasing the heating-surface. If from any cause, such as the insufficient capacity of the reservoirs and coil or too great a fire, more steam is generated than can be retained in the circulation, it will be forced upward through the pipe i into chamber or tank I, and if too great to be retained there it will be passed through the overflow-pipes i' down into the condensing-chamber K, located at the bottom and, consequently, at the coolest part of chamber E, where it will be quickly condensed, and may be drawn off, when desired, through waste-pipe k, or said waste-pipe may be left open for its escape. The heating-chamber E may be of any preferred construction, with fresh-air duct E¹ and hot-air pipes E² leading from its top to any and all parts of the house under any usual or preferred arrangement.

In practice, I prefer to make the inclosing-walls F of the heating-chamber of strong sheet metal, and to coat the same, either inside or outside, with a non-conducting cement of suitable material, such as a composition of asbestos and cement or lime, or other usual or preferred material, for this purpose.

The casing of the furnace may be similarly

coated, and also the exposed portion of the pipes $G G^1$, connecting the furnace with the heating-chamber, and the loss or escape of heat into the furnace-room thereby to a very great extent prevented.

Having thus described my invention, what I claim as new, and desire to secure by Letters Patent, is—

1. The annular water-reservoir and fire-pot $B B'$, made open at the top, as described, with its inclosing-case D placed outside of the heating-chamber, and combined therewith through the pipes $G G^1$ of the coil G^2 , the whole arranged and operating substantially as and for the purpose set forth.

2. The hot-water pipes or coil $G G^1 G^2$, connected with the fire-pot, as described, in combination with the water-reservoir H and water and vapor reservoir I , connected with the coil by pipes of less diameter, and operating substantially as described.

3. The overflow or condensing chamber K , in combination with the water and vapor reservoir I and overflow pipe or pipes $i' i'$, substantially as described.

H. F. HAYDEN.
